UNITED STATES PATENT OFFICE.

WILLIAM E. WILSON, OF MASON CITY, IOWA.

WALL CONSTRUCTION.

1,350,399.

Specification of Letters Patent. Patented Aug. 24, 1920.

Continuation of application Serial No. 752,419, filed March 6, 1913. This application filed October 24, 1917. Serial No. 198,713.

To all whom it may concern:

Be it known that I, WILLIAM E. WILSON, a citizen of the United States, residing at Mason City, in the county of Cerro Gordo and State of Iowa, have invented certain new and useful Improvements in Wall Construction, of which the following is a specification.

This invention relates to improvements in wall construction, and more particularly to such walls as are built of hollow building tile or other masonry construction.

It is a well known fact that in a great many walls of present day construction other than those embodying my invention, that one may stand close to a window within a room and by holding his hand adjacent the edges of the window casing will experience a distinct draft of cold air passing through the joints between said casing and the adjacent portions of the wall. Also when cracks occur in the plastering at the corners of a building, similar drafts of cold air may be experienced due to the passage of the cold air through cracks in the corner construction. Such is obviously very undesirable for many reasons, among which would be the added difficulty of heating the room, as well as the danger of the passage of moisture through such cracks and into the room. I have entirely eliminated these undesirable features in my new form of wall construction.

Among the objects of my invention is to prevent the passage of wind through such cracks between the window casing and wall or at the corner as referred to above; further to provide a more effective connection between the casing member of such openings as windows, doors, and the like, and the adjacent masonry construction; further to provide a novel form of corner construction, as a result of which not only will the entry of wind and moisture be prevented, but the strength of the wall will be greatly increased; further to combine in wall construction the maximum of strength, simplicity, economy, neatness, durability, and insulation against wind, dampness, and cold; and such further objects, advantages and capabilities as will later more fully appear.

This invention comprises improvements in the wall construction disclosed in my Patent No. 1,234,990, of July 31, 1917, and is a continuation of my co-pending applica-

tion, Serial No. 752,419, for wall construction, filed March 6, 1913.

My invention further resides in that combination, construction and arrangement of parts illustrated in the accompanying drawings, and while I have shown therein preferred constructions of my invention, I desire it to be understood that the same is susceptible of modification and change without departing from the spirit of my invention.

Referring to the drawings:

Fig. 1 is an isometric view of the form of block used in the construction of the wall.

Fig. 2 is a fractional portion of the block shown in Fig. 1, and formed by splitting the entire block through a vertical transverse plane.

Figs. 3, 4, 5, 6, and 7 illustrate further types of blocks embodying my invention, the outline of which is changed to suit varying conditions.

Fig. 8 illustrates the form of block shown in Fig. 5 when made use of in corner construction.

Figs. 9, 10 and 11 are transverse horizontal sectional views taken through that portion of the wall adjacent such openings as windows, doors, or the like, and showing typical construction used in providing such openings.

Fig. 12 is an isometric view, parts being shown in section to further illustrate the application of my inventive idea in forming such openings as windows, doors, or the like.

Fig. 13 shows a further adaptation in the construction of a more simple form of opening through the wall.

Fig. 14 is a sectional view taken on line 14—14 of Fig. 12, showing exaggerated the surplus space between the rib 10 and the sides of the groove 6 as being packed with corking or the like.

In the drawings, while I have shown the different forms of blocks as being formed of hollow tile, it is obvious that any form of construction embodying my inventive idea may be made use of. The various figures of the drawings illustrate the wide range of adaptabilities of my invention.

The block illustrated in Fig. 1 of the drawings is that form of block shown in my Patent No. 1,234,990, and used in the construction of the main portion of the wall. However, in the construction of such openings as windows, doors, and the like, I make use of some of this same form of block,

but placed with the voids arranged vertically, and there being interposed between every alternate block adjacent the window or door opening a fractional block such as shown in Figs. 2 and 12, the latter figure showing the actual arrangement of these blocks in the wall. The block of Fig. 1, as will be seen, consists of the two hollow transversely spaced lobes 1 and 2, which are separated by means of the webs 3 and 4, which webs are in turn spaced or inset from the sides of the block. The lobes 1 and 2 may be divided into any desired number of voids separated by the webs 5, which webs it will be noted are out of alignment with the webs 3 and 4. This construction is such as to result in the formation of the longitudinally extending grooves 6 and 7 in opposite faces of the block, the purpose for which grooves will later more fully appear. Upon each side of this block there may be formed kerfs 8 and 9, which serve as guides in splitting the block into fractional parts when desired. Similar kerfs may also be provided in webs 3 and 4 to facilitate the splitting of the block through a longitudinal plane if desired. One of the fractional parts formed by thus splitting the block is illustrated in Fig. 2, in which it will be seen that the longitudinal groove 6 is preserved intact. The adaptation of this form of block to the formation of openings in the walls, such as windows, doors, and the like, is clearly illustrated in Fig. 12, in which it will be seen that the fractional blocks alternate with the complete blocks, both of which are arranged with their voids in a vertical direction and with the grooves 6 in vertical alignment. These vertical aligned grooves are also in alignment with the similar grooves formed in the upper surface of the layer of horizontal blocks defining the lower limits of such opening in the wall.

In Fig. 12 I have shown at the bottom of the opening in the wall a sill 25, which may be of concrete, tile, terra cotta, brick, stone, marble, granite, or the like, and on the under face of which there may be the rib or tongue 26, which fits within the groove 6. However, this sill or lintel may be omitted and the bottom 41 of the casing member 44, both of which are provided on their exterior surfaces with the rib 45, may be applied directly to the upper surface of the main blocks with the rib in engagement with the groove 6 as shown in Fig. 13. The construction of Fig. 12 is that comprising the use of a box frame 40 to the back side of which is rabbeted or otherwise secured the vertically extending tongue or strip 10, which when in position extends into the groove 6. This construction is such as to provide by virtue of the entry of the tongue 10 within the groove 6, an absolute protection against the entry of wind from the exterior of the

wall through the joint between the casing and blocks to the interior of the room. Any free spaces that may exist between the rib 10 and the groove 6 may be additionally sealed by calking with hemp or other calking material as desired. Such calking would guarantee a further protection against the entry of wind. Attention is further called to the fact that the arrangement of the vertical blocks as shown in Fig. 12 in addition to providing vertical grooves for the reception of a wind seal, also seals the ends of the longitudinal passages in the horizontally arranged blocks in the main part of the wall. This form of connection between the window casing and the vertically arranged blocks is further of such nature as to afford an exceedingly rigid connection between the casing member and the wall.

As stated above, Fig. 13 shows the use of a more simple form of casing member, which is provided upon the outer surface with the longitudinally extending rib or tongue 45, which is adapted to fit within the longitudinally extending grooves 6, and also the vertically extending grooves 6. It is also to be noted in Fig. 13 that a slightly different form of vertical tile is used from that shown in Fig. 12, the form in Fig. 13 being a complete block but formed with only one void in each lobe instead of being split off from the larger block. In Fig. 13 every alternate course at the window or door opening is formed of a complete block, but only half as large as the one immediately above or below it. In Fig. 12 every alternate block adjacent the window or door opening is formed by splitting in half a block similar to the one immediately above or below it. Such half block is shown in Fig. 2 and is formed by splitting the block of Fig. 1 along the kerf 8. The inventive idea is the same in each case, and comprises the presentation of the vertically aligned grooves within which grooves fits either the tongue 10 of the box casing shown in Fig. 12 or the tongue 45 of the simpler form of casing member shown in Fig. 13.

Forms of vertical blocks illustrating the further adaptation of my inventive idea to the construction of such openings as windows, doors, or the like are illustrated in Figs. 9, 10 and 11, in Fig. 9 of which it will be seen that on one side of the vertically arranged blocks and adjacent the groove 6 is provided the projecting portion 11, which has been added to this portion of the block for the purpose of carrying out more complete architectural designs. This projection 11 virtually amounts to extending either the lobe 1 or 2 beyond or longer than the other for the architectural effect mentioned above. The extending of lobe 11 beyond the typical lobe 1 is made to comply with desired architectural effects only, and does not change the mechanical principle or the in-

ventive idea. The arrangement of the voids shown in Fig. 9 is to be considered as illustrative only and can be varied as desired to suit economical manufacturing conditions. 5 The box frame shown in Fig. 9 is provided upon one side with the longitudinally extending tongue 12, which in this case is made a part of the box frame, and when placed in operative position is inserted within the 10 groove 6. As referred to above in connection with Fig. 12, any surplus space occurring between the tongue 12 and the boundaries of the groove 6 may be packed with calking or insulating material. 15 The structure set forth in Fig. 10 is similar to that of Fig. 9, with the exception that the extension 11 has been provided upon the reverse side of the block, as also has the tongue 12 upon the reverse side of the box 20 frame 40, thus throwing these parts nearer the inside of the wall and upon the outer face of the wall there has been additionally provided the facing layer 13 of bricks, terra cotta, stone, or the like. 25 In Fig. 11 is illustrated a structure similar to that of Figs. 9 and 10, with the exception that for the form of block illustrated in Figs. 9 and 10, there has been substituted the form of block shown in Figs. 30 1 and 2, and also a simple form of casing instead of the box casing. This same simple, typical casing may also be applied in the instance when the facing of brick, terra cotta, or the like, is used upon the outside 35 of the wall.

The specific form of vertical block used in Fig. 9 is shown in detail in Fig. 3, and in placing these blocks in the wall, they are alternated with that form of block shown 40 in Fig. 4 in order to form a perfect bond. It is also pointed out that the form of block illustrated in Figs. 5 and 6 may be substituted for that shown in each of Figs. 1, 2, 45 3, 4, 9, 10 and 11, where thickness of wall or architectural design permits.

When it is desired to construct such openings as windows, doors, and the like, in rather close proximity with each other, I make use of the form of block shown in 50 Fig. 7 embodying the same inventive ideas pointed out above, but embodying the further feature that the provision of the extension 11 shown in Fig. 9 is duplicated on the opposite face of the block, thus resulting 55 in a form of block which, when placed in superposed relation in a wall, will result in a pier, column, or the like, and in connection with which the construction of openings for doors, windows, and the like 60 can be provided on each side of the block instead of on one side only, as illustrated in Figs. 9, 10 and 11. It is to be further noted 65 that the form of block shown in Fig. 7 is substantially identical with that shown in Fig. 1, with the exception that the block of

Fig. 7 has the extended lobes 11 instead of the lobes 1 and 2 having their faces in parallel relation. All of the figures so far described are typical illustrations only, and may be varied either in form of block or 70 form of casing or form of combination to suit architectural requirements, but still retaining the main inventive feature.

It is a well known fact that substantially the same requirements for the prevention of 75 the passage of wind, moisture, and the like, as occurs in the case of openings in walls as described above, also occurs in corner construction, and for the prevention of which at this point I have illustrated my 80 inventive idea in this connection in Fig. 8, in which it is seen that the vertically arranged hollow block illustrated in Fig. 5 is formed with the extension 11, groove 6, and lobe 1 heretofore described, with the course 85 of blocks A taking the same relative relation thereto as the casings or box frames above described, the packing (taking the form of a longitudinal insulating strip) 90 taking the place of the tongue on the frame and forming a tight insulating joint. The form of block used in Fig. 8 is of somewhat less thickness for a portion of its length and is substantially L shaped, the groove 6 being formed at the reentrant angle between 95 the foot portion and the main part of the block. This form of block used in constructing the corner of Fig. 8, and which block is illustrated in detail in Fig. 5, is provided 100 with the vertically extending voids 13, 14 and 15, the latter two of which are divided by the integral web 16, and are separated from the void 13 by the web 17. The foot portion of this L shaped block, which in other words, is the extension 11, is provided 105 with the vertically extending void 18. In this form of block, if desired, the web 16 may be omitted, making the voids 14 and 15 one void.

Having now described my invention, 110

I claim:

1. In a wall, the main body of which is composed of hollow tiles having spaced apart hollow lobes, the openings of which are arranged horizontally with a longitudinal groove therebetween in the upper and lower faces of said tiles, in combination similarly formed tiles arranged vertically to define an opening in the wall with their groove adjacent the opening in registry with the upper groove of the horizontal course of tiles forming the bottom of the opening, whereby to receive a rib on the casing of the opening to provide a wind seal between the casing and the wall. 115

2. In a wall, the main body of which is composed of hollow tiles having spaced apart hollow lobes, the openings of which are arranged horizontally with a longitudinal groove therebetween in the upper and 120

125

130

lower faces of said tiles, in combination with tiles having longitudinal openings therethrough and a longitudinal groove in one face, said last mentioned tiles being arranged vertically in the wall with their grooves in alignment with each other and with the vertical sides of the groove of a horizontal course of tiles, a casing member having a rib therein adapted to fit in said aligned grooves whereby to provide a wind seal between said parts.

3. In a wall formed of horizontal hollow tiles having spaced apart hollow lobes in combination with other hollow tiles having spaced apart hollow portions connected by spaced apart webs, which webs are in turn spaced from the sides of the block to form grooves, the hollow portions and webs of the last mentioned tiles being vertically arranged and a projecting portion on one of said hollow portions whereby in combination with one of said grooves to accommodate casing construction for windows, doors, or the like, and provide a wind seal.

4. In a wall formed of horizontal hollow tiles having spaced apart hollow lobes, in combination vertically arranged tiles having spaced apart hollow lobes connected by spaced apart webs, at least one of said webs being spaced from the side of the block to form a groove, one of said lobes being pro-

vided with a projecting portion having its side face flush with the side face of the lobe to which it is attached, whereby in combination with said groove to accommodate the construction of openings for windows, doors, or the like, and provide a wind seal.

5. In a wall construction, in combination, horizontal layers of hollow tile building blocks having horizontal passages therethrough, like layers of hollow tile building blocks arranged horizontally with the first layers, but set at an angle thereto and spaced therefrom at their adjacent ends, and superposed L shaped corner blocks fitting into the interspaces of said two sets of layers, the layer blocks being staggered and the corner blocks being reversed with respect to each other to fit between the adjacent offset parts of the layers, each corner block having a vertical bore divided by a vertical web and by another spaced web connecting said first mentioned web with the opposite wall integrally, the foot of the L having a vertical bore, and the wall of the main part of the block extending from said foot to the location of the first mentioned web being sunken below the outer surface of the block.

In witness whereof, I hereunto subscribe my name to this specification.

WILLIAM E. WHISON.
